UNITED STATES PATENT OFFICE.

FELIX EPSTEIN, OF BRUSSELS, BELGIUM.

MOBILE COUNTERBALANCED DEFLECTING BAFFLE.

Application filed October 13, 1927, Serial No. 226,032, and in Belgium October 16, 1926.

The present invention relates to an improved agitator or mixer fitted with mobile deflecting baffles.

According to this invention, a number of deflecting baffles—preferably mutually connected, and destined to bring about the mixing of several liquid or viscous materials or of one or more liquid or viscous materials with solids, the materials to be admixed being set in circular motion within a tank or other suitable vessel—are provided with counter-weights capable of keeping the baffles at the surface of the liquid contained in the vessel, independently of the level or the state of movement of the liquid. By means of the counter-weights, the baffles can be made to immerse in the liquid more or less deeply, at will. This equilibrated suspension of the deflecting baffles presents several advantages, notably the following:

(a) The baffles automatically adapt themselves to all changes of the level of the materials to be mixed;

(b) The live force of the materials to be mixed which are set in rotation by any appropriate process, is not in any way utilized to raise the baffles to the surface of the materials or to keep them there. This means a considerable saving of motive power.

(c) By increasing or diminishing the counter-weights in case pulleys are used, or by a simple displacement of the counter-weights along their levers, the baffles are easily adapted to any liquid.

The accompanying drawings represent one mode of realization of the present invention.

Fig. 1 is a longitudinal section of an agitator fitted with a system of mobile equilibrated deflecting baffles.

Fig. 2 is a transversal section thereof.

Fig. 3 is a longitudinal section of an agi-

tator fitted with the system in question, while in action.

Fig. 4 is a transversal section of the agitator while in action.

Within the vessel *m* there is a vertical axle *h* fitted with agitating arms *i*. The deflecting baffles *a* are connected by the chains or cables *b* running over pulleys *c* to the counter-weights *d*.

It is evident that the nature of the invention is in no way limited to the method of realization illustrated, and that the construction of the baffles, and more especially the method of applying the counter-weights can be realized in any other appropriate manner according to this invention.

I claim:

1. In a mixer having a vessel for containing the substances to be mixed and stirring means for setting the substances in rotation in the vessel, the combination of deflecting baffles suspended in said vessel and counter weight means acting on said baffles for maintaining the same automatically at the surfaces of the mass of substances to be mixed.

2. In a mixer having a vessel for containing the substances to be mixed and stirring means for rotating the same, the combination of deflecting baffles vertically movable in said vessel and means for exerting upon said baffles a continuous upward force independent of the state of rest or motion of the material in the vessel.

3. A mixer according to claim 2 wherein the upward force exerted by said last mentioned means is less than the weight of the baffles, but greater than the difference between the weight of the baffles and the weight of the material displaced by the immersion of said baffles.

FELIX EPSTEIN.
